UNITED STATES PATENT OFFICE.

JOHN C. WHARTON, OF NASHVILLE, TENNESSEE.

ROTARY ENGINE.

SPECIFICATION forming part of Letters Patent No. 720,542, dated February 10, 1903.

Application filed December 3, 1902. Serial No. 133,733. (No model.)

To all whom it may concern:

Be it known that I, JOHN C. WHARTON, of Nashville, in the county of Davidson and State of Tennessee, have invented a new and useful Improvement in Rotary Engines, of which the following is a specification.

My invention relates to rotary engines of the type shown, for instance, in Patent No. 96,262, dated October 26, 1869, in which two cylinders placed side by side are provided, respectively, with oppositely-moving pistons, which pistons are rigidly connected together by a diaphragm, which passes through from one cylinder-chamber to the other, the induction and exhaust ports being located on opposite sides of this diaphragm, one above and the other below the diaphragm, and which diaphragm rigidly connecting the rolling pistons has a tilting movement, as a lever upon a fulcrum, and also a sliding movement through the opening from one cylinder to the other, so as to accommodate the reverse rolling or scouring movement of the pistons when under the influence of the steam-pressure.

My invention comprehends certain novel constructions and arrangements of parts in this type of engine, which I will now proceed to describe with reference to the drawings, in which—

Figure 1 is a vertical transverse section through line 1 1 of Fig. 2. Fig. 2 is a horizontal longitudinal section through line 2 2 of Fig. 1. Fig. 3 is a vertical longitudinal section on line 3 3 of Fig. 2; and Fig. 4 is a side view of my engine, showing a system of "compounding."

A A' A A' A A' are three pairs of steam-cylinders arranged longitudinally side by side.

B B' B² B³ B⁴ B⁵ are eccentrics keyed to shafts C C' in the three respective divisions of the engine, marked between the dotted lines as division 1, division 2, and division 3 and formed by placing partitions A² A³ A⁴ A⁵ in the main cylinder or casing A A', which partitions are held by pins or set-screws s, as shown. The eccentrics in the different divisions of the casing project alternately in opposite directions. Thus B B' and B⁴ B⁵ project to the left and B³ B³ project (in opposition) to the right.

D D' D² D³ D⁴ D⁵ are pairs of cylindrical

ring-shaped piston-heads, the heads of each pair being rigidly joined by a diaphragm, as shown at G in Fig. 1. These ring-shaped heads inclose the eccentrics B B' and form rolling pistons, which scour around in their cylinders in opposite directions, causing the diaphragm to both tilt and slide.

Each pair of twin cylinders has an induction-port H and exhaust-port J opening, respectively, on opposite sides of the diaphragm G.

The three divisions of the engine are shown in Fig. 4 as compounded. With valves J' J² and H² H³ closed and H' J³ and N² N³ open steam enters through valve H', works in the first division, then through pipe N and valve N² passes to the induction-port of the second division, thence through the second division, acting expansively, and from its exhaust-port out through pipe N' and valve N³ to the induction-port of the third division, thence through exhaust-valve J³ into the waste-pipe. The three divisions may, however, work independently by opening valves H' H² H³ and J' J² J³ and closing valves N² N³, in which case steam passes in through H' H² H³ to each division of the cylinder and thence directly out at the top through J' J² J³. The diaphragm in each division passes through a slot from one cylinder to the corresponding one on the other side and rides on fulcrum-bars F F in the middle position, one being above and the other below the diaphragm.

At the middle point of each pair of cylinders and below the diaphragm G is the steam-induction port H and immediately above the diaphragm in the same vertical line is the exhaust-port J. Steam admitted through port H, Fig. 1, causes the piston B D to rise and move to the right, and the piston B' D' accordingly descends and moves to the right, causing the steam in this cylinder to be exhausted above the diaphragm in the right-hand cylinder, passing out through the exhaust-port J. In this movement the diaphragm G slides at first to the right between the fulcrum-bars F F and also tilts as a lever on the same to accommodate the reverse rolling or scouring action of the pistons in the two cylinders, the general path of movement of the two pistons being such as to describe a figure 8. Steam is alternately ad-

mitted to and exhausted from the opposite cylinder to continue this motion.

E E' E² E³ E⁴ E⁵ are eccentric-spaces formed between the eccentrics and the inclosing 5 rings in their respective divisions, (divisions 1, 2, and 3,) as shown in Fig. 2. As these crescent-shaped spaces constitute one of the important improvements of my invention, I call attention to the following points in regard to them. These eccentric-spaces are not concentric with the exterior circles of 10 cylindrical pistons D D', &c., but their centers are removed outwardly from the centers of D D', &c., so that the distances between the 15 centers of the eccentric-spaces E E', &c., are greater than the distances between the centers of piston-heads D D', &c., and by this construction they are also eccentric to the eccentrics B B', &c. In operation I would 20 state that in a compound engine as here described the differences between the eccentric-spaces and the eccentrics proper allow (and even compel) the shafts C C' to rotate at a uniform rate, whereas if the spaces 25 were not allowed in the construction (or an equivalent means of expansion and contraction allowed by a splicing of the diaphragm G, so as to provide for shortening it and lengthening it while in motion,) the engine 30 (compounded) would not run at all. The needed allowance for expansion and contraction is due to the fact that when the pistons D D' lie with their centers on the line 2 2 of Fig. 1, as shown, the distance between the 35 centers of eccentrics B B' is less than it is when the pistons are in any other position. The distance between the centers of eccentrics B B' is greatest when the centers have fallen upon lines at right angles to 2 2, as 40 they must fall in the course of revolution in the compounded form of engine here shown.

In connection with the engine as thus described I provide a flexible connection for the two shafts, which consists of a helical spring 45 S, whose ends are slipped over the ends of the shafts and rigidly attached thereto, the helical spring being for this purpose bent around one hundred and eighty degrees. The effect 50 of this flexible connection is to aid in regulating or synchronizing the relative movements of the two shafts. It is not essential, however, and may be omitted. A further office of this flexible connection is to act as a flexible fulcrum or instead of a fulcrum. It 55 may also be applied to the movement of external machinery, as in worm-gearing.

The engine as compounded permits it to be geometrically balanced in construction, which balancing is maintained while the engine 60 is in motion, thus allowing high speeds to be attained with a minimum or absence of vibration.

The multiplication of parts in the compounded engine tends to the uniform action of 65 its moving parts by averaging any of the common variations of wear or workmanship from a strictly theoretically-perfect construction.

The connection of the different compartments in "series" tends to utilize the full value of the steam by causing the leaks of 70 steam from one compartment to act on the pistons in succeeding compartments connected in the series, and in addition the steam may be expanded from smaller into larger compartments. 75

By the separation into compartments of the compound engine it is possible to use some of them simultaneously as steam-driven motors and others as air or water pumps, and also it permits taking into a smaller compartment 80 an explosive mixture, such as gasolene-vapor and air, and discharging the said mixture into a larger compartment and by igniting the said mixture to either reinforce or entirely replace the steam as a motive power, 85 or, in other words, to use the engine as a so-called "gasolene-engine."

In constructing the engine the partitions are preferably inserted in a continuous cylindrical chamber and secured by pins or set-screws, as shown, or the partitions may be connected and retained in any other desired way. 90

The fulcrums F F are not rigidly attached to the parts of the heads or partitions through 95 which they pass, but have a slight play or latitude of motion and are themselves springs, so as to yield slightly.

In order to have a balanced movement of parts, it is preferable to have the engine constructed with an odd number of compartments, as 3 5 7, &c., and to arrange the eccentrics and pistons in symmetrically-opposite positions on the shafts and to so proportion the parts that the two end compartments 100 shall together equal in size and weights of moving parts a middle compartment and that every alternate set of moving parts shall move in opposition to the next other set of moving parts. 105

What I claim as new is—

1. A rotary engine comprising two joined cylinders having an open communication between them at their tangential points and an induction and exhaust port one above and 115 the other below said tangential point, central shafts for the two cylinders having rigidly-attached eccentrics, ring-shaped piston-heads embracing the eccentrics and a sliding and tilting diaphragm rigidly connecting the piston-heads and passing through the middle opening between the cylinders, said ring-shaped piston-heads being constructed and arranged about the eccentrics to form crescent-shaped spaces between the internal periphery of the ring-shaped piston-heads and the external circumference of the eccentrics 125 substantially as described.

2. A rotary engine comprising two joined cylinders having an open communication between them at their tangential point, and an induction and exhaust port, one above and the other below the said tangential point, central shafts with rigid eccentrics arranged in 130

the cylinders, ring-shaped piston-heads embracing the eccentrics, a diaphragm rigidly connecting the two piston-heads, and two detachable fulcrum-rods, one arranged above and 5 the other below the diaphragm at the tangential line of the cylinders substantially as and for the purpose described.

3. A rotary engine comprising two joined cylinders having an open communication between them at their tangential point and an induction and exhaust port, one above and the other below said tangential point, central shafts with rigid eccentrics arranged in the cylinders, ring-shaped piston-heads embracing the eccentrics, a diaphragm rigidly connecting the piston-heads, and an external helical spring connecting the two shafts, substantially as and for the purpose described.

4. A rotary engine comprising a multiplicity of twin-cylinder divisions each consisting of a pair of cylinders tangentially joined and having an intercommunicating opening between them at their junction, shafts in the cylinders bearing rigid eccentrics with ring-shaped piston-heads embracing them, said ring-shaped piston-heads being rigidly connected by a diaphragm passing through the opening between the cylinders, and pipes and valves connecting the exhaust-port of one division of the engine with the induction-port of another division substantially as and for the purpose described.

5. A rotary engine comprising a multiplicity of twin-cylinder divisions, each consisting of a pair of cylinders tangentially joined and having an intercommunicating opening between them and an induction and exhaust port, shafts in the cylinders bearing rigid eccentrics with ring-shaped piston-heads embracing them, diaphragms rigidly connecting the two piston-heads of each pair and passing through the opening between the cylinders, a separate induction pipe and valve and also a separate exhaust pipe and valve for each

cylinder-division, and cross-pipes and valves, 45 each cross-pipe having one end communicating with the exhaust-port of one cylinder-division between it and its valve and the other end communicating with the induction-pipe of another cylinder-division between it and 50 its induction-valve substantially as and for the purpose described.

6. A rotary engine comprising a multiplicity of twin-cylinder divisions each consisting of a pair of cylinders tangentially joined and 55 having an intercommunicating opening between the cylinders and an induction and exhaust port as described, shafts in the cylinders bearing rigid eccentrics, the eccentrics projecting alternately in opposite directions 60 in the several divisions, ring-shaped piston-heads embracing the eccentrics and a diaphragm rigidly connecting the two ring-shaped piston-heads and passing through the opening between the cylinders substantially 65 as and for the purpose described.

7. A rotary engine comprising a multiplicity of twin-cylinder divisions each consisting of a pair of cylinders tangentially joined and having an intercommunicating opening between the cylinders and an induction and exhaust port as described, shafts in the cylinders bearing rigid eccentrics projecting alternately in opposite directions in the several 70 divisions, ring-shaped piston-heads embracing the eccentrics, and a diaphragm rigidly connecting the two ring-shaped piston-heads and passing through the opening between the cylinders, the longitudinal areas of the outer 75 divisions being smaller than the longitudinal areas of the inner division carrying the oppositely-projecting eccentrics substantially as described.
